PAUL KOLISCH, OF NEW YORK, N. Y.

METHOD AND MEANS FOR TRANSLATING SOUND

Application filed June 26, 1930. Serial No. 464,080.

This invention relates to sound recording or transmitting and especially to the recording of sound in the production of talking motion pictures.

5 One of the serious problems encountered during the recording of motion pictures and synchronized sound effects is the elimination of noise interference originating from sources which are not adapted to be completely silenced. For example, one great source of disturbance is the photographic camera itself, the mechanism of which produces during the operation, a sufficient hum or click to be recorded on the accompanying synchronized sound record in the form of an undesirable noise. Various attempts have been made in the past to prevent these sounds from reaching the microphone pick-up circuit which forms part of the sound recording system. One manner of reducing the interfering effect has been to place a silencing hood over the working mechanism of the camera or the placing of the camera and the operator thereof in a sound proof booth.

10 Each of these methods is open to objection; the hood interferes with the operation of the machine and does not completely muffle the sound, and the placing of the entire machine in a sound proof booth is not only an expensive and unwieldy method but also a hardship on the operator of the camera. Besides, both methods may necessitate photographing through a pane of glass.

15 It is an object of my invention to eliminate disturbing sound effects from sounds which it is desired to record or transmit. More specifically, it is an object of my invention to cause an undesirable sound effect to be balanced out or neutralized with respect to a translating instrument.

20 Another object is the provision of a photographic camera and sound recording arrangement whereby the effect of the camera noise on the recording mechanism is greatly reduced, and at the same time to provide means whereby the director of the recording process may issue verbal orders in an ordinary tone of voice without having his voice recorded on the record being produced by the 25 actors under his direction.

In accordance with my invention I provide a sound recording system wherein a plurality of microphone pick-up circuits are utilized in such manner that undesirable sounds are balanced out or neutralized and desired sounds picked up and recorded or otherwise dealt with. I accomplish this result by arranging two or more microphonic pick-up circuits so that a sound from an undesired source acts equally on the two circuits. These two microphonic circuits are in turn connected in opposition with a recording circuit so that if the amplitude of the sound on both of them is equal the result on the recording circuit will be the difference between the two effects or zero. The circuits are also so arranged that the sound from any source which it is desired to record, affects them unequally, the resultant after neutralization being dependent upon the difference in amplitude or 30 strength of the sounds affecting the two microphonic circuits.

35 In carrying out my invention I may place two pick-up microphones at equal distances from the disturbing sound source, which may be, for example, the photographic camera, and so select the positions of the microphones, camera and desired sound source, e. g. the actors, that the desired sound source is nearer to one of the microphones than to 40 the other. Alternatively, the distance between the microphones and the undesired source and between the microphone and the desired source may be the same and a baffle plate or other suitable means may be provided for causing the amplitude of the sound from the desired source to effect one microphone circuit more strongly than the other. With such an arrangement as this the two microphones may be placed very close together thereby simplifying the equipment and also rendering it more effective in neutralizing or balancing out undesired sounds which come from a variety of sources at different distances from the pick-up means. 45 The distance from the separate microphone pick-ups to the disturbing sound source should preferably be the same so as to insure that the various sound waves to be cancelled will arrive in the same phase relationship at 50

- the neutralizer in order completely to balance out or neutralize each other. When the disturbing sound has some particular frequency as would be the case with a certain type of 5 camera click, the microphones may be placed at unequal distances from the disturbing source and good results secured if each distance is so selected that the sounds arrive in substantially the same phase relationship.
- 10 In this case as the amplitude of sound varies inversely with the distance from the source, it will be necessary to adjust the amplification of the separate microphone pick-up circuits so that the two currents to be balanced out will be equal.

The microphones may be displaced either horizontally or vertically depending upon the particular conditions encountered. By displacing the microphones vertically the distance between each of them and any disturbing sources moving on a horizontal plane will remain substantially equal. Whereas if the microphones are displaced horizontally any relative moving of the microphones and the 20 disturbing sound source in a horizontal plane will result in the making of the distance between one microphone and the disturbing sound source different than that of the other microphone and the same sound source.

25 In order to permit the director of any recording process to give audible directions whatever his position may be with respect to the microphones, a loud speaker and extension mouth-piece or microphone may be furnished. The loud speaker is then considered as a disturbing sound source and located in a manner similar to that which I have already described in detail. The mouthpiece or microphone is carried by the 30 director and his orders issued to it at a sound amplitude so low that the main pick-up microphone circuits are not affected thereby. The sound received by the mouthpiece may then be amplified in the usual manner and 35 used to operate the loud speaker which will repeat the order in as loud a tone as desired. With such an arrangement the director is free to walk around as much as he wishes, carrying with him the mouthpiece which is 40 connected to the microphone and loud speaker through a flexible cord or other suitable arrangement. If desirable one link in the connection may be a suitable radio transmitting and receiving system, the sound being 45 converted into radio waves and being transmitted to a receiving set and where it is utilized in energizing a loud speaker.

The above mentioned and other objects and 50 advantages of my invention and the manner of attaining them will be made clear in the following description and accompanying drawings.

In the drawings, Fig. 1 is a diagrammatic view illustrating one application of my invention.

Fig. 2 is a view showing another arrangement which may be used.

Referring to Fig. 1, reference numerals 1 and 2 indicate pick-up microphones connected respectively to adjustable amplifiers 3 and 4. The output circuits of these amplifiers are connected to a balancer 5 which serves in any well known manner to transmit to an amplifier 6 the difference between the output currents of amplifiers 3 and 4. This balancer may comprise, for example, three coils mutually coupled, one of them serving as an output coil and the other two being coupled in the opposite sense to amplifiers 3 and 4 respectively so that the magnetic field of one of these last mentioned coils is opposed to that of the other, after the manner of a push pull transformer. The output of the amplifier 6 may be connected to any desired translating means such as a recorder or transmission line. 7 indicates a moving picture camera or other source of disturbing sound so located as to be equidistant from the two microphones. 8 is a source of sound which it is desired to record, e. g. an actor. This source may be moved over relatively large areas indicated roughly by the dotted line while still securing a good record. For convenience a circle or other closed figure may be defined on the ground or floor of the studio to indicate the area within which sounds will be properly recorded. As the source of sound 8 is located much nearer to microphone 1 than to 2, the amplitude of the output current of output 3 will be much greater than that of 4, therefore the output of balancer 5 will be some appreciable value as it represents the difference between the output currents of amplifiers 3 and 4. Current from the balancer 5 is fed to the amplifier 6 and then strengthened to the desired value. This current will represent, for the most part, the desired sound effects from source 8, the sound effects of source 7 being substantially neutralized or cancelled by the balancer. If the source 8 is sufficiently close to microphone 2 to have some effect on it, this may be reduced by the provision of a sound baffle or filter 9 placed between the source 8 and microphone 2 which acts to cut down the amplitude of the sound from that source reaching the microphone just mentioned. This baffle may be of any suitable material which has the power to prevent the passage of sound without causing harmful reverberations or echos. This baffle should be so located as to offer no more impedance to the sound passing between source 7 and microphone 1 than between source 7 and microphone 2. This may be done by placing the baffle edge-wise between the two microphones and pointing in towards source 7, as shown in Fig. 1. Of course, the baffle may be placed in a somewhat different position so that the sound path between the source 7 and one of the 100

microphones is less free than that between the source 7 and the other of the microphones, but in that case the gain of the microphones 3 and 4 should be so adjusted that their output currents representing sounds from source 7 are equal.

For permitting audible orders to be given by a director regardless of his position, loud speaker 10 is furnished. This is treated as a source of undesired sound and located with respect to the pick-up microphones in the same manner as source 7. The output currents of microphones 3 and 4 resulting from sound from loud speaker 10 are balanced out or neutralized in the same manner as currents resulting from the source 7. A mouthpiece or microphone 11 is provided for the director and is connected to the loud speaker through a flexible cable 12 or similar means, which is provided so that the director may carry the mouthpiece and move around without affecting the position of the loud speaker. An amplifier 13 of any suitable type may be interconnected between the mouthpiece and the loud speaker. If it is not desired to use a cable 12 or if the distance is too great for such uses, a connection between the mouthpiece and loud speaker may be made by radio in any well known manner.

According to the modification as shown in Fig. 2 an additional baffle 14 is provided. Instead of securing equalization of the output currents of the microphones with respect to the sound of source 7 by means of adjustable amplifiers, the baffle 14 might be moved back and forth until equality of the output currents of the microphones is secured. By spacing the microphones 1 and 2 apart a relatively great distance as shown in this figure, and placing the camera or other source of undesired sound between them, the effect of the desired sound on the second microphone, 2, is greatly reduced. As shown in this view the director or his microphone may occupy the position 15, corresponding to that of the camera 7.

Fig. 3 shows the two microphones 1 and 2 mounted very close together. With such an arrangement the baffle 9 is relied upon to prevent the sound from the desired source 8 from affecting the microphone 2 as strongly as it affects the microphone 1. The camera is arranged to affect both microphones in equal degree. By positioning the various pieces of apparatus in this manner, the distance between the different sources and each of the microphones need not be considered in determining their output currents; the amplitude of the sound wave from either source would be substantially the same upon arrival at each of the microphones except for the action of baffle 9. Instead of having the baffle, the two microphones may be pointed in opposite directions and placed side by side or back to back as shown in Fig. 4, and the directive

effect of the microphones relied upon to create the difference in the amplitude of the output currents thereof. By placing the mouthpieces of the microphones close together it will be assured that sound will reach the two at substantially the same instant.

Where recording is carried on indoors, precaution should be taken to prevent harmful reverberations or echoes which would tend to disturb the balance between the pick-up microphone with respect to the disturbing sound source. This may be done by the proper use of draperies or other sound absorbing or retarding devices. This phase of the recording art is well developed and so further comment with respect to it is not believed to be necessary.

In some cases it may be more convenient to record the outputs of microphones 1 and 2 separately and later combine them into a single noise free record. The two records should be combined in such manner that the effects of the undesired sounds upon the combined output neutralize or balance out. A difference in phase of the disturbing sounds received by each record may be corrected in the final record merely by causing the record produced by the microphone nearest to the disturbing sound source, to transmit its sound to a pick-up device over an air path or other delay means producing a phase shift equal to that produced by an air path equal to the difference between the distance from the disturbing sound source and one of the pick-up microphones and the same sound source and the other pick-up microphone. The currents from the pick-up device and currents produced directly from the other record may then be passed through amplifiers similar to 3, 4, and a balancer similar to 5. The output of the balancer will consist of the desired sound free from disturbance due to source 7.

Where the output currents of amplifiers 3 and 4 are unequal a balance in the neutralizer 5 may still be secured by adjusting the neutralizer to be affected by current from one amplifier more strongly than that from the other. If the neutralizer is the three coil transformer type this may be done by making the coupling different between the two primaries and the secondary.

What I claim is:

1. A sound translating system comprising in combination, a first microphone circuit for picking up sounds originating at a plurality of separated points, an adjustable amplifier therefor, a second microphone circuit for picking up said sounds, an adjustable amplifier for said second microphone and electrical means for combining the outputs of said amplifiers in opposed relationship.

2. A system according to claim 1 wherein a sound baffle is placed between the microphones of said microphone circuits.

3. A system according to claim 1 wherein

a sound baffle is placed between the microphones of the microphone circuits and a separate sound baffle is placed between one of said microphones and one of said separated points.

4. A system according to claim 1 wherein the two microphones are placed side by side close together and separated by a sound baffle.

10 5. A system according to claim 1 wherein the two microphones are of the directive type and are faced in different directions to secure a directive effect.

6. A system according to claim 1 wherein 15 the two microphones are of the directive type and are faced in different directions to secure a directive effect and are placed very close together so that the distance from each of said microphones to each of said separated points is substantially the same.

7. A system according to claim 1 wherein the two microphones are placed side by side close together and separated by a sound baffle which is directed toward the source of a 25 sound which it is desired to neutralize.

8. A sound recording system for segregating a sound generated at a first point from sound generated at a second point which comprises, a first sound pick-up device, a second 30 sound pick-up device, said devices being arranged to be affected equally by sound from said second point and unequally by sound from said first point, means for adjustably amplifying the output of said microphones to 35 different degrees, means for opposing the amplified currents, and means for recording the resultant.

9. The method of segregating sounds emitted from a plurality of separated points 40 which comprises selecting a pair of receiving locations such that sound from an undesired one of said points traverses each location in the same phase relation, and sound from a desired point traverses in substantial volume 45 only one of said locations, intercepting said sounds at said locations, transforming them into electric currents, equalizing the currents corresponding to the undesired sounds and subtracting the equalized currents of one of 50 said localities from the equalized currents of the other of said localities.

10. The method of recording the performance of an artist, which comprises selecting a pair of receiving locations, causing 55 sounds of said performance to reach said locations at a certain ratio of intensities, selecting a third location, issuing directing sounds from said third location, causing said sounds to reach said pair of locations at a different 60 ratio of intensities, translating sounds received at said pair of locations into electric currents, separately amplifying said currents to such degrees that the components thereof corresponding to sounds from said third 65 location are equalized, subtracting one of the

amplified currents from the other and utilizing the resultant current.

11. The method of recording the performance of an artist in the presence of an undesired source of noise, which comprises 70 selecting a pair of receiving locations, causing sounds of said performance to reach said locations at a certain ratio of intensities and sounds from said source of noise to reach said locations at a different ratio, translating sounds received at said locations into electric currents, separately amplifying said currents to such degrees that the components thereof corresponding to sounds from said source of noise are equalized, subtracting one of the 80 amplified currents from the other, and utilizing the resultant current.

12. The method of electrically selecting a desired sound from an undesired sound originating at a distance therefrom which comprises establishing a pair of receiving locations such that the desired sounds reach said locations at a certain ratio of intensities, and the undesired sounds reach it at a different 85 ratio, translating sounds received at said locations into electric currents, separately amplifying said currents to such degree that the components thereof corresponding to said undesired sounds are equalized, subtracting one of the 90 amplified currents from the other and utilizing the resultant current.

13. In a system for recording the performance of an actor or group of actors, a pair of pick-up microphones and a moving picture camera, said microphones being positioned at the ends of the base of an isosceles triangle, the camera at the apex thereof, the ends of said base being at points unequally distant from said actor, and a directing arrangement comprising a loud speaker positioned at the apex of an isosceles triangle having the same base as the triangle first mentioned.

14. A system for recording the performance of an actor or group of actors, comprising a pair of pick-up microphones and a moving picture camera, said microphones being positioned at the ends of the base of an isosceles triangle, the camera and a loud speaker at the apex thereof, the ends of said base being at points unequally distant from said actor, said loud speaker forming, in conjunction with a portable microphone, an amplifier, and means for interconnecting said microphone and loud speaker, an arrangement for directing said actor.

In testimony whereof: I have signed my name to this specification this 25th day of June, 1930.

EDWARD D. PHINNEY.
